STAY FOR WINDOWS OR THE LIKE

John Magnus Ragnar Ring, Ulvsunda,
Stockholm, SwedenApplication January 29, 1936, Serial No. 61,403
In Germany January 18, 1935

2 Claims. (Cl. 292—265)

The present invention relates to a device for safely operating, securing, and locking in various positions, windows, doors or the like which are adapted to be moved either in the inward direction or in the outward direction. So-called window stay devices for fixing a window or the like in a partly open position, are old. The said stay devices comprise a control rod or lever pivoted to the window frame or sash, respectively, or to an equivalent part, and provided with recesses, and a stopping member provided on the window sash or frame, respectively, or an equivalent part, the said stopping member being adapted to co-operate with the recesses of the rod in order to retain the same.

The purpose of the invention is to obtain a stay of the kind in question which also constitutes a window operating device and which is simple, consists of few, simple and little damageable parts, has no screws, springs, et cetera, and is easy to handle, and which, thus, may be operated silently and easily with one hand only and which at the same time is resistant and durable.

The problem has been solved according to the invention in such a way that the stopping member is embodied as a rotatably mounted sleeve or the like provided with a hole for the rod so that in an unsecured position the rod is guided in the sleeve with only insignificant play, and the lower limiting portion of the hole is given a shape exactly adjusted to co-operate with the recesses which here are provided on the underside of the rod. Thus, the stopping engagement of the rod and the sleeve is produced by moving the rod downwards or by the rod falling due to its own gravity. Its moving out of position and the operation of the window can be effected with one hand only by grasping the free end of the rod. Moreover, the rod is of such a length and the securing points of the same and the sleeve are located in such a way on the respective parts that the most advantageous lever action is obtained, viz. in such a way that the lever turning moment (torque) is increased when the window is being brought to the closing position so that less power is necessary to manipulate the window in the neighbourhood of this position, i. e. where the window might be subjected to the greatest resistance when closing same, on account of wind or the like, than in the neighbourhood of the quite open position.

At the closing of the window the rod is preferably adapted to be brought into engagement with a locking member on the window frame or sash, respectively, so that due to co-operation of the

locking member and the stopping sleeve, and to the indicated lever action the window will be effectively locked in the closed position. Thus, there is no risk of the window being opened until one has grasped the rod and completely controls the window.

Some embodiments of the invention are illustrated in the accompanying drawings, in which:—

Figures 1 to 3 show the operating and stopping device employed with an inwardly moving window;

Figure 1 being a front view of part of the window in closed position;

Figure 2 a plan cross section with the window in partly open position, and

Figure 3 a section along the line III—III of Figure 1.

In Figures 4 and 5, which show the device mounted on an outwardly moving window, Figure 4 is likewise a cross section, and Figure 5 a front section;

Figures 6 and 7 show on a larger scale an embodiment of an operating handle and a partial view of the operating rod respectively, the operating handle being embodied in another way.

1 indicates the window sash, 2 the window frame, and 2a the boarded window sill. One end of an operating and control rod 3 is pivoted to the window frame (Figures 1 to 3) or the window sash (Figures 4 and 5) respectively, and extends through a hole 4 in a socket or sleeve 5 or the like pivoted to the window sash or the window sill respectively, the said socket or sleeve forming a guide and stopping member for the rod. The size of the hole 4 is adjusted exactly to fit the rod 3, which in the embodiment shown has a cylindric shape so that the rod only moves with small play in the sleeve. The lower part (preferably half) of the hole has a rectangular shape; the lower edge portion 6 of the opening 4 is adapted to engage recesses 7 on the underside of the rod in order to fix the window in the desired position, and has a shape adjusted to fit the recesses. In the embodiment shown the recesses 7 are rectangular or approximately rectangular, in axial section and the engagement portion 6 has a corresponding shape so that a secure engagement is obtained.

At its free end the rod has an operating handle which may be shaped as an arched plate 50 or arm 8 which serves as a finger grip and is detachably secured (see particularly Figure 6) or as a ball 8' (Figure 7). The said operating handle also prevents the rod from leaving the sleeve.

The finger grip offers certain advantages over the ball handle, particularly due to the fact that it immediately indicates the operation of the rod and gives a sure engagement. The finger grip is fitted to the rod with the arched portion extending on one side or the other according as to whether the device is intended for left- or right-going windows. The arch-form of the engagement 8 may vary; the free end should be bent 10 in such a way as to eliminate the risk of clothes, curtains et cetera being caught therein. The recess in the rod end for the engagement may be arranged horizontally instead of vertically.

In the window sash or the window frame, respectively, there is provided a locking member 15 in the form of a fork-shaped projection provided with a notch 9, in which notch the free end portion of the rod is adapted to be inserted at the closing of the window. The bearing surface 9' lies at the same level as, or possibly somewhat 20 above the lower surface of the rod in free position. In order to facilitate the insertion there is provided a guide surface 10. Different forms of locking members may also be employed. The 25 rod is manufactured from some suitable metal or metal alloy, and should preferably be resilient so as to facilitate its moving in and out of locking position over the notch.

In Figures 1 to 3 (see particularly Figure 3) 30 the sleeve 5 is shown rotatably mounted in the legs of a U-shaped stirrup 11 or the like secured to the window sash. According to Figures 4 and 5 the sleeve is turnable in a fitting 12 secured to the window sill. 5' indicates the bearing of the 35 sleeve.

The rod is mounted with play in such a way 40 on a pin 13 secured to the end of a fork-shaped fitting 14 that the rod has a certain free motion relatively to the fixing point in the vertical position and also in the axial direction, if desired. This is necessary in order to permit the rod to 45 sink so as to engage the stopping sleeve, i. e., to a depth corresponding to that of the recesses 7, and it is also suitable in order to avoid the exact relative adjustment of rod, stopping sleeve and locking member 9 which else might be necessary at the mounting. In addition to the pin hole of the rod end having a somewhat larger 50 diameter than the pin in the axial direction of the rod the end 15 of the rod facing the fork arms is formed with a rounded taper (see particularly Figure 7). Thus, a constant contact 55 against the fork arms is ensured during the oscillating movements of the rod so that noise is avoided.

If desired, the surfaces 15 may be made spherical in order to enable a universal movement of the rod if this should prove necessary in order to 60 avoid jamming between rod and stopping sleeve or for some other purpose. The pin hole is then accordingly modified.

In the neighbourhood of the fixing point, the recesses 7 are provided nearer to each other and then farther from each other, and the distances 65 are adjusted in such a way that the window may be stopped in positions of about mutually equal distances around the arc in which the rod moves.

If the device is to be attached to an existing window, or possibly in other circumstances also, 70 it may be necessary to insert spacing washers under the fixing means for the rod or guide member or both so that said rod and guide member may be in correct alignment with each other or with the catch when the window is closed.

75 The length of the rod, the position of its fixing

point and the position of the sleeve are preferably adjusted so that an opening movement of about 90° may be imparted to the window and so that the most suitable lever relation is obtained. Thus, starting from closed window, the distance 5 between the inner (hinge) edge of the window sash and the fixing point of the rod should be larger than the distance between the said fixing point and that of the sleeve; the last distance, in its turn, being smaller than the distance 10 between the sleeve and the free end of the rod. Due to the fact that the pivot moves inwardly 15 relatively to the free end of the rod, the leverage of said free end increases with the movement of the window towards the closing position correspondingly increased turning moment with the operation of the window towards this position is obtained, and relatively less force is required for the said operation.

The function of the device is, in the first place, 20 connected with the above indicated lever relations so that the window may be operated by the rod with, so to speak, less power consumption than by a direct grip on the window. The device functions as follows. When the window is closed 25 the outer end of the control rod 3 is located in the notch 9; due to the above-stated lever moment of the rod and, to the fact that the rod rests closely against the edges of the hole of the sleeve an effective securing of the window is ensured 30 even if the other locking devices, if any, of the window are released. When opening the window one raises the control rod from the locking position by engaging, or grasping the operating handle, and moves the window inwards or outwards, 35 respectively, the rod gliding in the sleeve 5 during simultaneous turning of the sleeve. When the window has been opened to the desired extent the control rod is lowered or dropped so that the respective recess 7 will enclose the engagement portion 6 of the sleeve, the rod thus being 40 locked and the window stopped in the intended open position. In order to release the rod from the locking position one need only raise the same towards the upper edge of the hole 4 and then 45 the window may be freely operated again by the rod. When the window is being closed the outer portion of the rod glides or is moved upwards along the guide surface 10, and falls or is lowered into the notch 9 (Figure 3). 50

Modifications of the embodiment shown are, of course, possible. Thus, the rod may have another shape than cylindrical and the recesses of the rod may have other shapes. The stopping sleeve may be embodied and mounted in another 55 suitable way than the one shown.

The device may be used in windows having simple as well as double (coupled) sashes, and also in vertically swingable windows whereby it should be modified with respect thereto, and in doors of 60 various kinds.

Having now described my invention, what I claim as new and desire to secure by Letters Patent is:

1. In a stay device for windows, doors or the like having a hinged rod adapted to be adjusted and locked in different positions, the hinged rod being of substantially circular cross-section and provided in the known manner on the underside with notches, a substantially U-shaped bracket 70 mounted on said sash, a guide member mounted rotatably in the legs of said bracket and having an aperture in its lower portion, said rod passing through said aperture, a stationary pivot on the window frame nearer than is said bracket to the 75

axis of rotation of the window sash and a grip on said rod so that the window sash can be opened by pulling the grip of the rod.

2. In a stay device for windows having a fixed frame and a window sash hinged to said frame, a window actuating stay rod hingedly attached to said frame, a substantially U-shaped bracket

mounted on said sash, a guide member mounted rotatably in the legs of said bracket and having an aperture in its lower portion, the rod passing through said aperture and having transverse grooves therein and the lower portion of the guide member having a projection to fit said grooves. 5

JOHN MAGNUS RAGNAR RING.
